UNITED STATES PATENT OFFICE.

ADAM J. HOBART, OF ST. JOHNSVILLE, NEW YORK, ASSIGNOR TO F. ENGELHARDT & SONS, OF ST. JOHNSVILLE, NEW YORK.

PNEUMATIC ACTION FOR PIANOS AND SIMILAR MUSICAL INSTRUMENTS.

986,288.

Specification of Letters Patent.

Patented Mar. 7, 1911.

Application filed January 31, 1910. Serial No. 541,019.

To all whom it may concern:

Be it known that I, ADAM J. HOBART, a citizen of the United States, residing at St. Johnsville, county of Montgomery, State of New York, have invented new and useful Improvements in Pneumatic Actions for Pianos and Similar Musical Instruments, of which the following is a specification.

This invention relates to an improved construction of the pneumatic action which is controlled by a music sheet and actuates the hammers of a piano or similar musical instrument. The action is compact, simple in construction, and effectively checks leakage at the valves, so that a reliable transmission is obtained, while waste of power is avoided.

In the accompanying drawings: Figure 1 is a front view of part of my improved pneumatic action, showing the same applied to the piano hammer actuating means; Fig. 2 a plan of Fig. 1, with some of the parts omitted; Fig. 3 a vertical transverse section on line 3—3, Fig. 1, and Fig. 4 an enlarged transverse section on line 4—4, Fig. 2.

My improved pneumatic action comprises a pair of superposed valve boxes or blocks 10 and 11, extending preferably across the entire width of the piano and arranged in front of the lifters that actuate the piano hammers. Near its ends, lower block 10 is supported upon the flanges 12 of the upright main vacuum pipes 13, while upper block 11 is spaced from block 10 by a pair of intermediate stays 14, one end section only of the blocks being shown in the drawing. As the lower sides of blocks 10 and 11 are beveled for the attachment of the action bellows 15 and 16, respectively, triangular fillers 17 are interposed between block 10 and flanges 12, and between block 11 and stays 14, all these parts being firmly united by thumb-screws 18, as illustrated in Fig. 3. Bellows 15 are adapted to actuate alternate hammers of the piano, while bellows 16, that stagger with bellows 15, are adapted to actuate the hammers located intermediate those first mentioned. For this purpose, the movable board of each bellows is provided with a tappet 19 extending below the cushioned head of a screw 20 which engages a bracket 21 secured to lifter 22. The latter actuates its hammer through wippen 23, in the usual manner.

For collapsing bellows 15 and 16, each block 10 and 11 is provided with a pair of

vacuum chambers 24, 25, from which the air is constantly withdrawn through pipes 13 and upright channels 26 formed in fillers 17 and stays 14. As the lower block 10 is a duplicate of upper block 11, the invention 60 may be understood by confining the description to the upper block.

For each bellows 16 there is provided a primary valve and a secondary valve, which valves are controlled by a perforation in the 65 music sheet, as usual. The primary valve consists of a longitudinally fluted stem 27 guided in a pair of bushings 28 fitted into a corresponding bore 29 of block 11 and carrying a pair of valve-disks 30, 31 cushioned as at 32. Bushings 28 are preferably provided with flanges 33, the outer diameters of which are smaller than those of cushions 32, so that the edges of the latter extend beyond those of the former. In 70 this way the frequently, more or less, rough rims of the cushions do not contact with the valve seats, so that undue leakage is avoided, while, for the same reason, the valve-disks are not liable to stick to their 75 seats. Into the lower end of stem 27 is screwed a button 34 which is provided with peripheral notches 35 for the engagement with a suitable gripping tool, so that by turning the button, its distance from valve-disk 31 may be adjusted. Button 34 rests upon a diaphragm 36 secured to the bottom of chamber 24. Below the diaphragm, block 11 is provided with a shallow recess 37 that permits a slight sagging of the diaphragm. 90

The stem 38 of the secondary valve which is aligned with the stem of the primary valve transversely to the wind chest of the instrument is guided in a pair of perforated bars 39, of which one is secured to a longitudinal 95 rail 40 supported by block 11, while the other is arranged within vacuum chamber 25. Stem 38 carries a pair of cushioned valve-disks 41, 42, playing in a chamber 43 and adapted to engage flanged bushings 44. 100 The latter are fitted into corresponding bores of block 11 and rail 40, the diameters of disks 41 exceeding those of bushings 44, for the reasons above given. To the bottom of stem 38 is secured a button 45 resting upon a diaphragm 46 which is secured to the bottom of vacuum chamber 25 below said button, block 11 being provided with a shallow recess 47 for accommodating said diaphragm. 105

The perforated music record controls, in the usual manner, by means of a tracker bar (not shown), a flexible tube 48 for the pneumatic action for each of the piano hammers. 5 Tube 48 communicates with a pipe 49 inserted into a front flange 67 of a board 50 which is secured to block 11. Pipe 49 opens into a port 51 of flange 67 which communicates through an angular duct 52 with recess 37, said duct being also connected with vacuum chamber 24 through a bleed hole 53. I prefer to interpose between port 51 and duct 52, a wire netting 54 which retains all dust or other solid particles entering 15 through tube 48. Netting 54 and port 51 may be readily cleaned by removing a button 55 which normally closes said port. Bore 29 communicates through a passage 56 with recess 47, while chamber 43 is, by duct 20 57 and opening 58 of bellows 16, connected with the interior of said bellows. For adjusting the stroke of the movable board of bellows 16, the latter is provided with a cushion 59 which is adapted to be engaged 25 by the cushioned head of a screw 60 tapped into block 11 and passing through duct 57 and opening 58.

In order to deaden the sound of the upper primary and secondary valves, I prefer to 30 secure to block 11 and rail 40, above said valves, a pair of inverted U-shaped hoods 61, 62 which are open at both ends to permit free access of air. The sound of the lower 35 valves is prevented from diffusing by a longitudinal upright plate 63 arranged intermediate boards 50.

The air inlet ports of lower board 50 are, by pipes 64 and flexible tubes 65 connected to the lower protruding ends of pipes 66 extending through the upright perforations of flange 67, said perforations being formed in 40 said flange intermediate ports 51. The upper ends of pipes 66 are by flexible tubes 48, connected to the tracker bar of the instrument. 45

The operation of the device will be readily understood. The uncovering of any perforation of the tracker bar admits air below the diaphragm 36 of the corresponding 50 primary valve, so that the latter will ascend to admit air through passage 56 below diaphragm 46 of the secondary valve. The latter will thus also rise to connect the coöperating action bellows with vacuum chamber 55 25. The bellows will thus collapse to raise

tappet 19, which will, in turn, raise lifter 22 to actuate the piano hammer. After the perforation in the tracker bar has again been covered by an imperforate section of the music record, the air will be withdrawn 60 through bleed hole 53 from the recess below diaphragm 36, so that the primary and secondary valves will descend to permit the expansion of the action bellows.

With instruments of the class described in 65 which the pneumatic action is located in the forward part of the case, it is of importance that the depth of the action be reduced to the greatest extent possible, in order to not unduly enlarge the dimensions of the case. 70 With a tier construction of valve blocks, it is obvious that the connections between the primary valves of the lower tier and the tracker bar are obstructed by the valve block of the upper tier, so that without further 75 means, it would be necessary to locate said lower valve connections in front of the upper block. By applicant's device this waste of space is entirely obviated and the upper valve block is utilized not only for the purpose of receiving the pipe connections of the upper tier, but also for sustaining and 80 accommodating the pipe connections for the lower tier which are interposed between the inlet ducts of the upper tier, so that in this 85 way the proper co-relation of the parts is maintained.

I claim:

A device of the character described, comprising an upper block having a front flange 90 and a plurality of ports and upright perforations extending alternately through said flange, a lower block, a plurality of primary and secondary valve chambers in each block, means for maintaining the blocks at a distance from each other, a first set of air inlet pipes fitted into the upper block flange and communicating with the ports of said flange, a second set of pipes fitted into the perforations of the flange, a third set of pipes fitted 95 into the lower block, and tubes connecting the second set of pipes with the third set of pipes, the pipes of the first and third sets communicating respectively with the primary valve chambers of the upper and lower 100 blocks.

ADAM J. HOBART.
